UNITED STATES PATENT OFFICE.

CHARLES H. PARSHALL, OF NEW YORK, N. Y., ASSIGNOR TO JOHN KEENAN, OF SAME PLACE.

ROTARY VALVE.

SPECIFICATION forming part of Letters Patent No. 674,684, dated May 21, 1901.

Application filed January 5, 1901. Serial No. 42,209. (No model.)

To all whom it may concern:

Be it known that I, CHARLES HENRY PARSHALL, a citizen of the United States, residing at New York, borough of Manhattan, and 5 State of New York, have invented certain new and useful Improvements in Rotary Valves, of which the following is a specification.

This invention relates to valves for the expander of refrigerating apparatus such as 10 shown and described in my copending application, Serial No. 740,868, filed December 19, 1899; and the object of the same is to provide a valve with a peculiar means of adjustment for compensating for the expansion and 15 contraction of its casing.

My invention consists, further, of certain features of construction and combinations of parts to be hereinafter described and then particularly claimed.

20 In the accompanying drawings, Figure 1 is an enlarged detail perspective view of the expander, illustrating the valve-gear which may be employed. Fig. 2 is a transverse section through the slide and guide of the valve-gear. Fig. 3 is a detail perspective view of the crank, arm, and pivoted dog of the cut-off valve. Fig. 4 is a longitudinal central section of the expander. Fig. 5 is a perspective view of the upper set of valves of the 25 expander and their casing. Fig. 6 is a section on the line 6 6 of Fig. 5 through the valve on the off side of the upper part of the expanding-cylinder; and Fig. 7 is a section on line 7 7, Fig. 6.

30 The expander A is provided at its upper and lower ends, respectively, with valve-casings F G, the open-ended cylindrical shell of the expander being provided with a centrally-located cylindrical partition a, which forms the 35 expanding-chamber a'. Arranged at one side of the expanding-chamber a' are two air-chests a² a⁴, which are separated from each other by means of a web or partition a⁶, while on the opposite side of the expanding-chamber there are two similar air-chests a³ a⁵, which are separated from each other by a 40 horizontal web or partition a⁷, the chests a³ a⁵ at one side being separated from the chests a² a⁴ at the opposite side by means of vertical partitions a⁸. (Indicated in dotted lines in Fig. 4.) The valve-casing F consists of two

cylindrical valve-chambers f f', respectively, separated by a central web or partition f². The valve-chamber f is provided with two ports f³ f⁴, communicating with the air-chest 55 a² and expanding-chamber a', respectively, while the valve-chamber f' is provided with two ports f⁵ f⁶, communicating with the expanding-chamber a' and the air-chest a³, respectively.

60 The valve-casing G at the lower part of the expander consists of two cylindrical valve-chambers g g', respectively, separated by a central web or partition g². The valve-chamber g is provided with two ports g³ g⁴, communicating with the air-chest a⁴ and expanding-chamber a', respectively, while the valve-chamber g' is provided with two ports g⁵ g⁶, communicating with the expanding-chamber a' and air-chest a⁵, respectively.

65 Contained in each of the valve-chambers f f' g g' is a valve H H' H² H³, respectively, of the same size and shape as the valve-chamber and each arranged to close its respective port communicating with the expanding-chamber. The radius of the face of each valve corresponds with the radius of the valve-chamber, so that when the face of the valve is against the seat surrounding the port it can effectively shut off all communication between the valve-chamber and the expanding-chamber. The valve H is opposed to the port 70 f⁴, forming the communication from the air-chest a² to the expanding-chamber a'.

75 i represents the inlet, by means of which the air is admitted to the air-chest a². As the air while in said air-chest a² is of a practically normal temperature, there will be no material contraction or expansion of the casing of the valve-chamber f. The valve H 80 therefore snugly fits the valve-chamber f, and as the pressure of the air from the air-chest a² to the expanding-chamber a' normally presses the valve toward its seat at f⁴ and as the air from the air-chest a² does not cause 85 any material expansion or contraction of the casing of the valve-chamber f it is not necessary to provide the valve with any adjustment device, such as hereinafter described. The valve H', which is arranged within the 90 valve-chamber f' and is substantially cylindrical in shape, has its sides cut away at f⁵

and the top of the valve cut away at f^0 , so that the top of the valve will have slightly less size than the valve-chamber in order that the valve H' can be adjusted to compensate 5 for the expansion and contraction of the casing of the valve-chamber f' , as hereinafter set forth.

Referring more particularly to Figs. 6 and 7, the shaft K of the valve H' is provided at 10 one end with a stuffing-box k , projecting through the valve-casing into the valve-chamber f' . The inner face of the stuffing-box k is grooved vertically at k' to provide a vertical guide, in which is contained a movable 15 block k^2 . The end of the valve-chamber f' opposite the stuffing-box k is provided with a vertical guide k^3 , opposed to the guide k^2 , and contained in the guide k^3 is a movable block k^4 . Journaled in blocks $k^2 k^4$ is the 20 shaft K of the valve H' . One end of the shaft K projects through and beyond the outer face of the stuffing-box k , so that it may be properly connected with the valve-gear hereinafter described. Projecting through the top of 25 the casing of the valve H' are two set-screws k^5 , which are screwed into correspondingly-threaded bores or holes arranged vertically above the center of the shaft K , one set-screw being opposed to each movable block. 30 Formed in the top of each of the movable blocks $k^2 k^4$ is a recess k^6 , in each of which recesses there is arranged a spring k^7 , bearing against the bottom of its respective recess and the inner end of the set-screw. The 35 purpose of the springs k^7 is to normally hold the valve H' against its valve-seat, formed around the port f^5 , which communicates with the expanding-chamber a' , and the purpose of the set-screw k^5 is to regulate the pressure 40 of the said springs. The bore of the stuffing-box k is slightly greater in diameter than the diameter of the shaft K in order that the said shaft can have a limited movement to allow of its vertical adjustment by the 45 blocks $k^2 k^4$. The valve H is provided with a shaft K' , journaled in the stuffing-box k^8 and in the inner end of the valve-casing thereof. Valves $H^2 H^3$ correspond, respectively, with the valves $H H'$, the valve H^3 being 50 provided with an adjusting device similar to the adjusting device of the valve H' . Each of the valves is substantially cylindrical in shape, and, like the valve H' , has one of its sides cut away to form a port or recess to register with the port of its respective valve-chamber communicating with the expanding-chamber. The valves $H H^2$ may also be provided with adjusting devices similar to those of the valves $H' H^3$; but it is not 55 necessary, however, to provide the said valves with this adjusting device, as the action of the air on these valves continuously presses them against their respective valve-seats f^4 g^4 , while in the case of the valves $H' H^3$ the 60 air is continuously forcing them from their seats. The offports of the valves $H' H^3$

could not be used as seats against which the said valves may work, inasmuch as there is a tendency for ice to form at the said sides of the valves, and consequently there would 70 not be an easy action and a proper fit. The piston J of the expanding-chamber a' is provided with a piston-rod J' , which is guided through the usual stuffing-box in the valve-casing G at the lower part of the expander 75 and has the well-known pitman-and-crank connection with the drive-shaft.

The air is admitted into the expander through the inlet i , which leads directly into the air-chest a^2 , and by means of the ports $f^3 f^4$ 80 from the air-chest a^2 to the expanding-chamber a' at a point above the piston J , where it is expanded by the action of the downward stroke of the piston and then exhausted through the ports $f^5 f^6$ into the air-chest a^3 , the 85 valve H controlling the passage of the air from the air-chest a^2 into the expanding-chamber a' , and the valve H' controlling the passage of the air from the expanding-chamber a' to the air-chest a^3 . The motions of the valves $H H'$ 90 are so timed and the valves are so arranged in relation to each other that when the valve H is moved to uncover the ports $f^3 f^4$ from the air-chest a^2 to the expanding-chamber a' the valve H' is moved to cover the ports from the 95 expanding-chamber a' to the air-chest a^3 in order that the downward reciprocating action of the piston will properly expand the air in the expanding-chamber. The valve H uncovers its ports for admitting air into the expanding-chamber a' during the first quarter 100 of the downward stroke of the piston and then immediately closes the port, the other valve H' remaining closed also. Thus the air in the expanding-chamber is expanded to 105 at least four times its own volume by the single downward stroke of the piston J . When the piston makes a stroke in the opposite direction, or upward, the valve H' is moved by its properly-timed valve-gear to uncover the 110 port f^5 and establish a communication from the expanding-chamber a' into the air-chest a^3 , and when the piston has completed its stroke the said valve is moved to cover the 115 port and closes the communication between the expanding-chamber and air-chest a^3 , the valve H being simultaneously moved to uncover the port from the air-chest a^2 into the expanding-chamber a' , so that the described 120 action may be repeated and the air repeatedly expanded within the expanding-chamber. The expanded air is led from the air-chest a^3 to the air-chest a^4 by means of the inclined communicating pipe l (indicated in dotted lines in Fig. 4) and is admitted, by 125 means of the port controlled by the valve H^3 , from the air-chest a^4 into the expanding-chamber a' at a point below the piston J , where it is again expanded by the reciprocating action of the piston and afterward exhausted from 130 the expanding-chamber a' through the port controlled by the valve H^3 into the air-chest

a^5 , from whence it passes through the outlet i' into the pipe D' to perform its refrigerating action in the ice-box D .

In order to cause the valves to properly coact, so as to control the admission and exhaust of the air, it is necessary to provide them with a suitable valve-motion, such as shown in my said copending application and which may be constructed as follows: Referring to Fig. 1, m^2 is a connecting-rod leading from a suitable power device to the valves. On the shaft K of the valve H' is fixed a bell-crank lever N , one arm n of which is connected to the eccentric-rod m^2 by means of a link m^3 , so that by means of the eccentric-rod m^2 the bell-crank lever N and the valve H' can be rocked to open or close the port leading from the expanding-chamber a' . O O' indicate, respectively, slideways fixed to the expanding-cylinder above and below the valve-casings F G , and P represents a sliding block arranged so as to be longitudinally reciprocated along the slideway O . (See Fig. 2 for detail.) The top of the block P is provided with a recess p , adapted to receive an adjustable tooth p' , having an inclined face p^2 and a stem p^3 passing through and projecting below the lower edge of the block P . P' represents a plate connected to the lower edge of the block P by means of set-screws P^2 and by means of which the plate can be vertically adjusted to or away from the bottom of the sliding block P . The lower end of the stem p^3 of the tooth p' rests upon the plate P' , and by means of said plate and the stem p^3 the tooth p' can be adjusted vertically. The other end n' of the bell-crank lever N is connected with one end of a link n^2 , while the other end of the link is connected to the sliding block P , the consequence of this connection being that during the operation of the valve H' the bell-crank lever N causes the reciprocating movement of the sliding block P . From Fig. 3 it will be more clearly seen that shaft K' of the valve H projects suitably beyond its stuffing-box, so as to overhang the slide-block P , said shaft K' carrying at its projecting end a resisting-lug q , the upper end of which is bifurcated and is provided around the shaft K' with a sleeve q' . Said sleeve is rigidly secured to the shaft K' and is preferably so arranged as that the lug q is located vertically above the adjustable tooth p' . Pivotaly hung, by means of its hub r' , on the valve-shaft K' is a dog r , said hub of the dog being held between the forked part of the sleeve q' of the resisting-lug q and arranged to swing on the valve-spindle K' away from the resisting-lug q upon the movement of the slide-block P in the direction of the arrow, Fig. 1. During the movement of the slide-block P in the opposite direction indicated the adjustable tooth p' engages the pivoted dog r and carries the same along with it, the dog during its forward movement coming in contact with the resisting-lug q , and thereby causing the rotation of the valve-shaft K' and the

valve H . During the return movement of the sliding block P in the direction of the arrow the inclined face p^2 of the adjustable tooth p' engages the pivoted dog and swings it away from the resisting-lug q , and as soon as the tooth p' clears the dog the dog gravitates into normal hanging position, so that it may be moved against the resisting-lug upon the reverse movement of the slide-block P . The shaft K' of the valve H is provided with a crank-arm S , to which is connected a rod S' , which terminates in a dash-pot S^2 , as shown clearly in Fig. 1. 80

The action of the valve-gear described in connection with that of the valves H and H' is the following: The rod m^2 , link m^3 , and arm n move the bell-crank lever upwardly, turning the valve H' so as to close the port from the expanding-chamber a' to the air-chest a^3 . This movement of the bell-crank lever causes the arm n to draw the link n^2 and sliding block P toward the valve H' , which movement causes the adjustable tooth p' to engage the pivoted dog r and turn the valve H so as to open the port from the air-chest a^2 into the expanding-chamber a' . As soon as the adjustable tooth has cleared the pivoted dog r the valve H is immediately turned to close the port from the air-chest a^2 to the expanding-chamber a' by the drawing action of the dash-pot S^2 . The air admitted to the expanding-chamber a' from the air-chest a^2 is, as before stated, now cut off by the valve H 100 during the piston-stroke at a point where the best results may be obtained. When the piston J has reached the end of its downward stroke, the valve H is moved to uncover its port from the expanding-chamber into the air-chest a^3 , which remains uncovered during the entire upward stroke of the piston, the air at this part of the operation being expanded to four times its original volume. The air after being exhausted from the expanding-chamber into the air-chest a^3 is exhausted from the latter into the air-chest a^4 , the valve H^2 of which air-chest is operated similarly to that of the valve H . The air is exhausted from the air-chest a^4 into the expanding-chamber a' below the reciprocating piston J 110 during its upward stroke, where it is again expanded, and is then exhausted at the downward stroke of the piston into the air-chest a^5 , the valve H^3 of which has an adjusting device constructed similarly to that of the valve H' and is provided with a bell-crank lever T , similar to the bell-crank lever N , said lever T being pivotally connected with the connecting-rod m^2 and link m^3 . A valve-motion similar to the valve-motion between the bell-crank lever N and the valve-shaft K' is arranged between the bell-crank lever T and the valve-shaft K^2 of the valve H^2 , and the detailed description of the other suffices for the latter 120 valve-motion. The slide-block for the lower valve-motion reciprocates on the guide O' , before referred to. The valves are so arranged in relation to each other that when the valve

H is opened the valve H' is closed and when the valve H² is opened the valve H³ is closed, and vice versa. The shaft K² of the valve H² carries a crank-arm T', to which is connected a connecting-rod T², that terminates in a dash-pot T³. Thus it will be seen that the upper and lower sets of valves have substantially the same valve-gear.

The valves described are very reliable and practical in action and are especially adapted for an expander for refrigerating apparatus of the type shown.

Having thus described my invention, I claim as new and desire to secure by Letters Patent—

1. The combination, with the valve-casing, the valve-shaft journaled in the valve-casing, and the valve carried by the valve-shaft, of guides suitably formed in the ends of the valve-chamber, and bearing-blocks mounted in said guides and in which said valve-shaft bears, substantially as set forth.

2. The combination, with the valve-casing, the valve-shaft journaled in the ends of the casing, and the valve carried by the valve-shaft, of guides in the ends of the valve-chamber, bearing-blocks mounted movably in said guides and through which the valve-shaft extends, and means for adjusting the bearing-blocks, substantially as set forth.

3. The combination, with the valve-casing, and the valve carried by the valve-shaft, of guides in the ends of the valve-chamber, bearing-blocks in which the shaft turns, said blocks being arranged in said guides, and set-

screws opposed to the bearing-blocks, so as to vary the pressure of the valve on its seat, substantially as set forth.

4. The combination, with the valve-casing, the valve-shaft journaled in the casing, and the valve mounted on the valve-shaft, of guides at the end of the valve-chamber, bearing-blocks guided by said guides and through which the shaft extends, said bearing-blocks being provided with recesses, springs contained in the recesses, and set-screws engaging said springs, substantially as set forth.

5. The combination, with the valve-casing, the valve-shaft, and the valve mounted thereon, of a stuffing-box for one end of the valve-chamber, said stuffing-box having a bore of larger diameter than the valve-shaft, which passes therethrough, guides formed in the inner end of the stuffing-box and the opposite end of the valve-chamber, bearing-blocks contained in said guides and through which the valve-shaft extends, said bearing-blocks being provided with recesses, set-screws passing through the casing of the valve-chamber opposite to the bearing-blocks, and springs confined in said recesses by the set-screws, whereby the pressure of the valve on its seat may be varied, substantially as set forth.

In testimony that I claim the foregoing as my invention I have signed my name in presence of two subscribing witnesses.

CHARLES H. PARSHALL.
